(57) **CLAIM**

The ornamental design for a projector screen with stand, as shown and described.

DESCRIPTION

FIG. 1 is a perspective view of a projector screen with stand showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 2; and,

FIG. 11 is an enlarged view of portion 11 shown in FIG. 2. The broken lines in the drawings depict portions of the projector screen with stand that form no part of the claimed design. The dash dot dash broken lines in FIG. 1, FIG. 2, FIG. 9, FIG. 10 and FIG. 11 are for the purpose of depicting areas of enlargement to show details and form no part of the claim.

1 Claim, 11 Drawing Sheets
